(57) **CLAIM**

The ornamental design for a portable rugged dehumidifier, as shown and described.

DESCRIPTION

FIG. 1 is a top left elevation view of a portable rugged dehumidifier showing our new design;

FIG. 2 is a top right elevation view of thereof;

FIG. 3 is another top left elevation view thereof;

FIG. 4 is another top right elevation view thereof;

FIG. 5 is a bottom right elevation view of thereof;

FIG. 6 is a bottom left elevation view of thereof;

FIG. 7 is another bottom right elevation view of thereof;

FIG. 8 is another bottom left elevation view of thereof;

FIG. 9 is a left plan view thereof

FIG. 10 is a right plan view thereof;

FIG. 11 is a back plan view thereof;

FIG. 12 is a front plan view thereof;

FIG. 13 is a top plan view thereof; and,

FIG. 14 is a bottom plan view thereof.

The broken lines shown throughout these figures depict environmental subject matter only and form no part of the claimed design.
